UNITED STATES PATENT OFFICE.

VINCENZO MASSACESE, OF NEW YORK, N. Y.

CUSHION-SPRING CONNECTION.

Application filed April 20, 1926. Serial No. 103,363.

This invention relates to cushion spring structures, and has particular reference to an improvement in the means for connecting the spring units to the frame.

5 As an object the invention contemplates an improved means of connecting the spring units of a cushion spring to the frame, which insures a rigid and positive connection and precludes any possibility of accidental disconnection.

10 The invention further comprehends a connection of the character set forth which is extremely simple, economical, and highly effective.

15 With the above recited and other objects in view, reference is had to the following specification and accompanying drawings in which there is exhibited one example or embodiment of the invention which is in no way 20 intended as a limitation upon the scope of the appended claims as it is to be clearly understood that variations and modifications which properly fall within the scope of said claims may be resorted to when found expedient.

In the drawings—

Figure 1 is a fragmentary plan view of a framed cushion spring illustrating the spring units joined to the frame by a connection made in accordance with the invention;

Fig. 2 is a fragmentary plan view illustrating the relative position of the parts in the initial step of attaching the spring;

Fig. 3 is a sectional view therethrough taken approximately on the line 3—3 of Fig. 2 and illustrating the connecting loop partially bent around the frame;

Fig. 4 is a plan view illustrating the connecting loop bent downwardly over the frame;

Fig. 5 is a sectional view taken approximately on the line 5—5 of Fig. 4;

Fig. 6 illustrates the connecting loop wrapped about the frame;

Fig. 7 is a sectional view thereof taken on the line 7—7 of Fig. 6;

Fig. 8 illustrates the final position of the connecting loop with its terminal wrapped about the spring convolution and with the bight engaging the frame;

Fig. 9 is a sectional view taken on the line 9—9 of Fig. 8.

Referring to the drawings by characters of reference 10 designates the frame of a cushion spring structure and 11 the spring units

which are connected to each other by the connections 12 in the usual well-known manner.

The present invention appertains to the means for connecting the outermost or marginal spring units to the frame, and said means consists of a length or lengths of material 13, such as wire, which are bent and formed to provide portions 14 wrapped respectively about portions of the frame and 65 portions of the convolutions of the spring units. The portions 14 are in the nature of U-shaped offsets which are spaced coincident with the spacing of the spring units 11 and which include side arms 15 joined by a bight 70 16. The ends or terminals of the length of material or wire 13 are provided with loops 17 which are wrapped about end convolutions of the spring units. The portions or offsets 14 are, initially threaded over the 75 spring unit end convolutions as illustrated in Fig. 2 and under the frame 10 and are thence bent upwardly as in Fig. 3 and downwardly to wrap the arms around the frame as illustrated in Figs. 4 and 5. The side arms of the 80 loops 14 converge toward each other from their juncture with the main portion of the wire or length of material 13 to the bight 16 so that the portions thereof toward the outer 85 end or bight when wrapped around the frame may be then bent downwardly as in Figs. 6 and 7, to lie between the wider portions. The remaining ends of the arms are thence bent inwardly and upwardly over the 90 spring convolutions until the bight 16 is 95 brought into contact with the frame 10 as illustrated in Figs. 8 and 9, which illustrates the finished joint. By looping, bending and forming the length of material or wire as 100 illustrated, it is obvious that an extremely strong, rigid and durable connection between the spring units and frame is established which positively precludes accidental disconnection and insures a rigid structure due to 105 the fact that the material or wire 13 is of a sufficient gage to resist straining of the wrapped portions by a pull exerted in a direction to effect relative separation of the spring units and frame. It is apparent, however, that when a disconnection is desired, 110 a reversal of the steps employed in establishing the connection may be easily accomplished by individually unwrapping the wrapped portions.

From the foregoing it will be seen that a connection between the spring elements of a cushion spring and its frame has been de-

vised which is economical yet strong, durable and efficient.

What is claimed is:

In a spring structure, a frame, springs, and
5 a length of wire provided with U-shaped offset loops having converging members, each loop being bent under and over the end convolution of a spring, under and over the frame

and then under and over the said convolution of a spring with its end extending between the members of the loop towards the frame, whereby the frame and the spring are held in separate encircling portions and thereby a rigid connection between the spring and frame obtained.

VINCENZO MASSACESE.
